UNITED STATES PATENT OFFICE.

WALTER M. WELLMAN, OF NEW HAVEN, CONNECTICUT, ASSIGNOR TO THE NATIONAL FOLDING BOX AND PAPER COMPANY, OF SAME PLACE.

DESIGN FOR A BOX-BLANK.

SPECIFICATION forming part of Design No. 30,160, dated February 7, 1899.

Application filed December 14, 1898. Serial No. 699,286. Term of patent 7 years.

To all whom it may concern:

Be it known that I, WALTER M. WELLMAN, a citizen of the United States, residing in the city of New Haven, county of New Haven,

5 State of Connecticut, have invented and produced a new and original Design for a Box-Blank, of which the following is a specification, reference being had to the accompanying drawing, forming part thereof.

10 The figure of the drawing is a plan view of the blank showing my new design.

As shown in the drawing, the leading or essential feature of my design consists in the shape of the box-blank, comprising the rela-

tive arrangement and individual shape of the 15 eleven united panels, as shown in the drawing, the dividing-mark between any two panels consisting of a creased line.

Having described my invention, what I claim as new, and desire to secure by Letters 20 Patent, is—

The design for a box-blank as herein shown and described.

WALTER M. WELLMAN.
